[57] **ABSTRACT**

Compounds of the formula

wherein R¹ is alkyl of 1 to 4 carbons,

pyridyl, thienyl or furyl; R is hydrogen, alkyl of 1 to 4 carbons, hydroxy-alkyl of 1 to 4 carbons, alkanoyl of 2 to 5 carbons, or

wherein alkyl is of 1 to 3 carbons, n is an integer from 1 to 4; and X, X¹, X² and X³ are independently selected from hydrogen, chlorine, fluorine, trifluoromethyl, alkyl of 1 to 4 carbons and alkoxy of 1 to 4 carbons; are disclosed. These compounds including their pharmaceutically acceptable acid-addition salts, quaternary ammonium salts, and N-oxides are useful as antimicrobial and antifungal agents.

11 Claims, No Drawings

SUBSTITUTED PYRAZOLO[4,3-C]PYRIDINE COMPOUNDS

SUMMARY OF THE INVENTION

This invention relates to new compounds of the formula:

and the pharmaceutically acceptable acid-addition salts, quaternary ammonium salts, and N-oxides thereof which have been found to exhibit antimicrobial and antifungal activity when administered to mammalian species.

R¹ represents alkyl of 1 to 4 carbons,

pyridyl, thienyl or furyl.

R represents hydrogen, alkyl of 1 to 4 carbons, alkanoyl of 2 to 5 carbons, hydroxy-alkyl of 1 to 4 carbons or

wherein alkyl is of 1 to 3 carbons,

n is an integer from 1 to 4.

X, X¹, X² and X³ are independently selected from hydrogen, chlorine, fluorine, trifluoromethyl, alkyl of 1 to 4 carbons, and alkoxy of 1 to 4 carbons.

The term "alkyl" is intended to include both straight and branched chain radicals, as for example, methyl, ethyl, propyl, isopropyl, butyl, t-butyl, etc. The term "alkoxy" includes such alkyl groups attached to an oxygen atom, i.e., methoxy, ethoxy, propoxy, isopropoxy. The term "alkanoyl" is intended to include such alkyl group attached to

i.e., acetyl, propionyl, etc.

The term "acid addition salts" is intended to mean salts which may be formed for the purposes of isolation, purification, and storage, such as the oxalate salt, picric salts, etc. and pharmaceutically acceptable salts meant for administration of the compound to a host, such as the hydrochloride, sulfate, acetate, maleate, citrate salts, etc.

The N-oxide may be formed by dissolving the free base of Formula I in a solvent inert to hydrogen peroxide, e.g., ethanol or chloroform, adding excess (on a molar basis) hydrogen peroxide, and allowing the mixture to stand at room temperature for several hours. An acid-addition salt of the N-oxide may be formed by addition of the desired acid, for example, those mentioned above.

The quaternary ammonium salts include those formed with alkyl halides (e.g., methyl chloride, isobutyl bromide, dodecyl chloride and cetyl iodide), benzyl halides (e.g., benzyl chloride) and dilower alkyl sulfates (e.g., dimethyl sulfate).

DETAILED DESCRIPTION OF THE INVENTION

The new compounds of formula I are prepared by reacting a pyrazolo[4,3-c]pyridine of the formula

with a compound of the formula

wherein halo is either chlorine or bromine. The reaction is performed in the presence of a suitable solvent such as benzene, toluene, ether, or dimethylformamide at a temperature of from about 20°C to the reflux temperature of the solvent for from about 4 to about 24 hours, preferably from about 6 to about 20 hours.

When n is 2, it is preferred to prepare the compounds by reacting the compound of formula II with a vinyl ketone of the formula

35 The vinyl ketone is available either directly as the compound of formula IV, i.e. where R¹ is methyl one employs 3-buten-2-one, or as a compound which can be reacted so as to provide the ketone of formula IV, i.e. where R¹ is phenyl one heats 3-(dimethylamino)-1-40 phenyl-1-propanone which liberates

45

The preparation of the pyrazolo[4,3-c]pyridine of formula II is disclosed in U.S. patent application Ser. No. 340,408, filed on Mar. 12, 1973.

50 As disclosed in that application, 4-piperidinone or preferably an N-acyl derivative thereof, e.g. the N-acetyl or N-benzoyl derivative, is reacted with an aldehyde of the formula

55 utilizing the reaction procedure described in the Journal of the American Chemical Society, 70, 1824 60 (1948) to give the compound of the formula

hours. The solvent is removed on a rotary evaporator to leave a solid residue which on trituration with ether and cooling gives 9.5 g. of crude product; m.p. 210°-212°. Crystallization from 250 ml. of ethanol yields 6.0 g. of light yellow 3,3a,4,5,6,7-hexahydro-2-methyl-3-phenyl-7-(phenylmethylene)-2H-pyrazolo[4,3-c]pyridine, hydrochloride; m.p. 218°-220°. The hydrochloride salt is treated with K_2CO_3 to yield the free base.

c. 1-(4-Fluorophenyl)-4-[2,3,3a,4,6,7-hexahydro-2-methyl-3-phenyl-7-(phenylmethylene)-5H-pyrazolo[4,3-c]pyridin-5-yl]-1-butanone, hydrochloride (1:1)

A mixture of 7.0 g. (0.023 mole) of 3,3a,4,5,6,7-hexahydro-2-methyl-3-phenyl-7-(phenylmethylene)-2H-pyrazolo[4,3-c]pyridine from part (b), 6.0 g. (0.03 mole) of 4-chloro-1-(4-fluorophenyl)-1-butanone, 6.0 g. (0.057 mole) of pulverized Na_2CO_3 , and 75 ml. of dimethylformamide is stirred and refluxed for 20 hours. The bulk of the dimethylformamide is removed on a rotary evaporator at 2 mm. and the cooled residue is shaken with 100 ml. of $CHCl_3$ and 50 ml. of water. The layers are separated and the aqueous phase is extracted with $CHCl_3$ (2 × 50 ml.). The combined $CHCl_3$ layers are washed with water (3 × 50 ml.), dried ($MgSO_4$), and the solvent evaporated to give 13.2 g. of a reddish oil. This oil is taken up in 100 ml. of methyl ethyl ketone and treated with 3.9 ml. of 6.0 N alcoholic HCl. The methyl ethyl ketone liquor is poured into 700 ml. of stirred ether to precipitate a solid which is filtered under N_2 , washed with ether, and dried in vacuo to yield 4.9 g. of residue; m.p. 121°-125° (foaming); s. 80°. This residue is stirred with 25 ml. of isopropyl alcohol, and after cooling overnight, the insoluble solid is filtered, washed with isopropyl alcohol and ether, and dried in vacuo to yield 1.1 g. of crude product; m.p. 175°-178°. Crystallization from 7 ml. methanol — 70 ml. ether yields 0.9 g. of light yellow solid 1-(4-fluorophenyl)-4-[2,3,3a,4,6,7-hexahydro-2-methyl-3-phenyl-7-(phenylmethylene)-5H-pyrazolo[4,3-c]pyridin-5-yl]-1-butanone, hydrochloride (1:1); m.p. 180°-182°.

EXAMPLE 2

1-(4-Fluorophenyl)-4-[2,3,3a,4,6,7-hexahydro-3-phenyl-7-(phenylmethylene)-5H-pyrazolo[4,3-c]pyridin-5-yl]-1-butanone, hydrochloride

Following the procedure of example 1 but substituting hydrazine for the methylhydrazine in part (b), one obtains 1-(4-fluorophenyl)-4-[2,3,3a,4,6,7-hexahydro-3-phenyl-7-(phenylmethylene)-5H-pyrazolo[4,3-c]pyridin-5-yl]-1-butanone, hydrochloride.

EXAMPLES 3-23

Following the procedure of example 1 but employing the appropriate substituted benzaldehyde in part (a) and the appropriate hydrazine in part (b) one obtains the following compounds of formula II shown in Col. A which are converted to the products of formula I shown in Col. B.

Col. A

Col. B

EXAMPLES 24-55

Following the procedure of Example 1 but substituting for the 4-chloro-1-(4-fluorophenyl)-1-butanone in part (c) the compounds shown in Col. A one obtains the products shown in Col. B.

Additionally, by reacting the compounds of Col. A in examples 24 to 55 with the compounds of Col. A in examples 3 to 23, other compounds within the scope of the invention are obtained.

EXAMPLE 56

4-[2,3,3a,4,6,7-Hexahydro-2-methyl-3-phenyl-7-(phenylmethylene)-5H-pyrazolo[4,3-c]pyridin-5-yl]-2-butanone, hydrochloride (1:1)

A stirred solution of 6.0 g. (0.02 mole) of 3,3a,4,5,6,7-hexahydro-2-methyl-3-phenyl-7-(phenylmethylene)-2H-pyrazolo-[4,3-c]pyridine from example 1(b) in 60 ml. of dimethylformamide is treated with 1.9 ml. (0.022 mole) of 98.5 percent 3-buten-2-one and kept overnight at room temperature. The solution is then poured into 600 ml. of cold water and the oily product is extracted with ether (5 × 100 ml.). The combined extracts are washed with water (3 × 100 ml.), dried (MgSO₄), and the solvent evaporated to give 7.3 g. of light yellow glass-like base. This base is dissolved in 40 ml. of acetonitrile, treated with 3.3 ml. of 6.0 N HCl, and diluted to 200 ml. with ether. The

HCl salt separates initially as an oil, but on rubbing crystals appear. The material is allowed to crystallize at room temperature for several hours and then is cooled overnight to yield 7.4 g. of crude product; m.p. 181°-183° (dec.). Crystallization from a mixture of 80 ml. of warm methanol and 400 ml. of ether (solution initially) yields 5.2 g. of light yellow solid 4-[2,3,3a,4,6,7-hexahydro-2-methyl-3-phenyl-7-(phenylmethylene)-5H-pyrazolo[4,3-c]pyridin-5-yl]-2-butanone, hydrochloride (1:1); m.p. 185°-187° (dec.).

EXAMPLE 57

3-[2,3,3a,4,6,7-Hexahydro-2-methyl-3-phenyl-7-(phenylmethylene)-5H-pyrazolo[4,3-c]pyridin-5-yl]-1-phenyl-1-propanone, hydrochloride (1:1)

A stirred mixture of 5.0 g. (0.0165 mole) of 3,3a,4,5,6,7-hexahydro-2-methyl-3-phenyl-7-(phenylmethylene)-2H-pyrazolo[4,3-c]pyridine from example 1(b) and 3.6 g. (0.0168 mole) of 3-(dimethylamino)-1-phenyl-1-propanone, HCl in 100 ml. of ethanol is heated and the resulting solution is refluxed for six hours. The ethanol is allowed to distill off gradually into a Dean-Stark tube to help remove by-product, dimethylamine, while fresh solvent is added intermittently through an additional funnel to maintain the volume at approximately 100 ml. After standing overnight at room temperature, the bulk of the ethanol is removed on a rotary evaporator to give a gummy residue which is shaken with 250 ml. of ether. A portion of the residue dissolves leaving some solid undissolved. The undissolved portion is filtered, washed with ether, and dried in vacuo to yield 2.9 g. The ether filtrate is evaporated to give 5.9 g. of a light yellow foamy residue which is redissolved in 250 ml. of ether, stirred, and treated with alcoholic HCl until no more solid separates. This solid material is filtered under N₂, washed with ether, and dried in vacuo to yield 6.4 g. which is combined with the 2.9 g. previously obtained and then stirred for one hour with 75 ml. of water, filtered, washed with water, and air dried to yield 5.1 g. of crude pale yellow product; m.p. 175°-177° (dec.). Crystallization from 200 ml. of ethanol yields 3.8 g. of colorless 3-[2,3,3a,4,6,7-hexahydro-2-methyl-3-phenyl-7-(phenylmethylene)-5H-pyrazolo[4,3-c]pyridin-5-yl]-1-phenyl-1-propanone, hydrochloride (1:1); m.p. 182°-184° (dec.).

EXAMPLES 58-66

Following the procedure of example 56 or 57 but employing the vinyl ketone shown below in Col. A one obtains the final products shown in Col. B.

Col. A	Col. B

66	

35 Similarly by employing the compounds shown in Col. A of examples 3 to 23 in the procedure of examples 56 to 66, other compounds within the scope of the invention are prepared.

EXAMPLE 67

1-(4-Fluorophenyl)-4-[2-acetyl-2,3,3a,4,6,7-hexahydro-3-phenyl-7-(phenylmethylene)-5H-pyrazolo[4,3-c]pyridin-5-yl]-1-butanone, hydrochloride

45 A mixture of 10 g. of 1-(4-fluorophenyl)-4-[2,3,3a,4,6,7-hexahydro-3-phenyl-7-(phenylmethylene)-5H-pyrazolo[4,3-c]pyridin-5-yl]-1-butanone, hydrochloride from example 2 and 250 ml. of acetic anhydride is refluxed for four hours. The solution is concentrated on a rotary evaporator and the residue is cooled and triturated with ether to yield 1-(4-fluorophenyl)-4-[2-acetyl-2,3,3a,4,6,7-hexahydro-3-phenyl-7-(phenylmethylene)-5H-pyrazolo[4,3-c]pyridin-5-yl]-1-butanone, hydrochloride.

50 55 Similarly, by employing the substituted benzaldehydes from examples 3 to 23 or the compounds from Col. A of examples 24 to 55 or other acylating agents such as propionyl chloride in the procedures of example 2 and example 67, other compounds within the scope of the invention are obtained.

EXAMPLE 68

3-[2,3,3a,4,6,7-Hexahydro-2-methyl-3-phenyl-7-(phenylmethylene)-5H-pyrazolo[4,3-c]pyridin-5-yl]-1-phenyl-1-propanone, N-oxide

60 65 The hydrochloride salt of example 57 is basified by treatment with K₂CO₃. A solution of the free base in ethanol is then treated with two equivalents of 30 per-

cent H_2O_2 . The solution is allowed to stand for two days and the solvent is removed under reduced pressure to give 3-[2,3,3a,4,6,7-hexahydro-2-methyl-3-phenyl-7-(phenylmethylene)-5H-pyrazolo[4,3-c]pyridin-5-yl]-1-phenyl-1-propanone, N-oxide.

EXAMPLE 69

3-[2,3,3a,4,6,7-Hexahydro-2-methyl-3-phenyl-7-(phenylmethylene)-5H-pyrazolo[4,3-c]pyridin-5-yl]-1-phenyl-1-propanone, methochloride

The hydrochloride salt of example 57 is basified by treatment with K_2CO_3 . A solution of the free base in acetonitrile is cooled and treated with methylchloride. The solution is allowed to stand for one day and the solvent is evaporated to give 3-[2,3,3a,4,6,7-hexahydro-2-methyl-3-phenyl-7-(phenylmethylene)-5H-pyrazolo[4,3-c]pyridin-5-yl]-1-phenyl-1-propanone, methochloride.

Similarly the compounds of any of examples 1 to 56 or 58 to 67 can be treated according to the procedures of example 68 or 69 to obtain the N-oxide or quaternary ammonium salt of other compounds within the scope of this invention.

EXAMPLE 70

The following is a cream formulation which is applied topically to the skin to treat dermatophytosis.

Ingredient	% by weight
4-[2,3,3a,4,6,7-Hexahydro-2-methyl-3-phenyl-7-(phenylmethylene)-5H-pyrazolo[4,3-c]pyridin-5-yl]-2-butanone, hydrochloride (1:1)	1.0%
Cetyl alcohol	2.2%
Glyceryl monostearate	9.4%
Spermaceti	5.5%
Isopropyl palmitate	2.2%
Propylene glycol	12.0%
Polyoxyethylene sorbitan monostearate	3.3%
Purified water	64.4%

What is claimed is:

1. A compound of the formula:

wherein R^1 is selected from the group consisting of alkyl of 1 to 4 carbons,

pyridyl, thienyl, and furyl; R is selected from the group consisting of hydrogen, alkyl of 1 to 4 carbons, hydroxy-alkyl of 1 to 4 carbons, alkanoyl of 2 to 5 carbons, and

wherein alkyl is of 1 to 3 carbons; n is an integer from 1 to 4; X^1 , X^2 and X^3 are independently selected from the group consisting of hydrogen, Cl, F, alkyl of 1 to 4 carbons, alkoxy of 1 to 4 carbons, and CF_3 ; and the pharmaceutically acceptable acid-addition salts, N-oxides, and quaternary ammonium salts thereof.

2. The compound of claim 1 wherein R^1 is selected from the group consisting of alkyl of 1 to 4 carbons and

R is selected from the group consisting of hydrogen, alkyl of 1 to 4 carbons, and benzyl; X , X^1 , and X^2 are independently selected from the group consisting of hydrogen, Cl, F, CF_3 , CH_3 and OCH_3 .

3. The compound of claim 2 wherein R is alkyl of 1 to 4 carbons and X and X^1 are the same.

4. The compound of claim 3 wherein R is methyl, R^1 is selected from the group consisting of methyl and

X and X^1 are the same and are selected from the group consisting of hydrogen, Cl, and F; X^2 is selected from the group consisting of hydrogen, F, and Cl; n is 2 or 3.

5. The compound of claim 4 wherein X and X^1 are both hydrogen.

6. The compound of claim 5 having the name 4-[2,3,3a,4,6,7-hexahydro-2-methyl-3-phenyl-7-(phenylmethylene)-5H-pyrazolo[4,3-c]pyridin-5-yl]-2-butanone, hydrochloride (1:1).

7. The compound of claim 5 having the name 3-[2,3,3a,4,6,7-hexahydro-2-methyl-3-phenyl-7-(phenylmethylene)-5H-pyrazolo[4,3-c]pyridin-5-yl]-1-phenyl-1-propanone, hydrochloride (1:1).

8. The compound of claim 5 having the name 1-(4-fluorophenyl)-4-[2,3,3a,4,6,7-hexahydro-2-methyl-3-phenyl-7-(phenylmethylene)-5H-pyrazolo[4,3-c]pyridin-5-yl]-1-butanone, hydrochloride (1:1).

9. The method of preparing compounds of the formula

which comprises reacting a compound of the formula

with a compound of the formula

or

wherein R is hydrogen, alkyl of 1 to 4 carbons, hydroxy-alkyl of 1 to 4 carbons, or

wherein alkyl is of 1 to 3 carbons; halo is Cl or Br; and R¹, n, X, X¹, X² and X³ are as defined in claim 1.

10 15 10. The method of preparing compounds of the formula

wherein alkyl is of 1 to 4 carbons which comprises a compound of the formula

with an acylating agent of the formula

5

wherein alkyl is of 1 to 4 carbons; halo is Cl or Br; and R¹, n, X, X¹ and X² are as defined in claim 1.

11. The method of preparing compounds of the formula

which comprises reacting a compound of the formula

with a compound of the formula

wherein R is hydrogen, alkyl of 1 to 4 carbons, hydroxy-alkyl of 1 to 4 carbons, or

40

wherein alkyl is of 1 to 3 carbons; and R¹, n, X, X¹, X² and X³ are as defined in claim 1.
